UNITED STATES PATENT OFFICE.

FRANCIS K. FASSETT, OF ST. LOUIS, MISSOURI, ASSIGNOR TO LEO EHRLICH, OF ST. LOUIS, MISSOURI.

REGISTER.

SPECIFICATION forming part of Letters Patent No. 791,616, dated June 6, 1905.

Application filed December 17, 1903. Serial No. 185,529.

To all whom it may concern:

Be it known that I, FRANCIS K. FASSETT, a citizen of the United States, residing at the city of St. Louis, State of Missouri, have invented a certain new and useful Improvement in Registers, of which the following is a full, clear, and exact description, such as will enable others skilled in the art to which it appertains to make and use the same, reference being had to the accompanying drawings, forming part of this specification, in which—

Figure 1 is a face view, partly in section, certain of the parts being broken away to more clearly illustrate other parts and a portion of the casing and of the dial being broken away in order to economize space. Fig. 2 is an elevation, partly in section. Fig. 3 is an elevation, partly in section, the section being taken on a line different from that on which the section of Fig. 2 is taken. Fig. 4 is a fragmentary elevation looking from the right of Fig. 3, the side wall of the casing being removed. Fig. 5 is an enlarged top plan view illustrating certain details of construction, the ratchet-plate being partly broken away. Fig. 6 is an enlarged elevation showing particularly one of the numbering-disks and the parts intimately associated therewith. Fig. 7 is a sectional view illustrating the keyholes. Fig. 8 is a fragmentary view illustrating the bit portion of the key which controls the shutter. Fig. 9 is a view of a similar character illustrating the key for controlling the clockwork mechanism. Fig. 10 is a side elevation of the key or tool which operates the totalizer-shaft. Fig. 11 is an end elevation of the same. Fig. 12 is a fragmentary top plan view illustrating a modification, a portion of the gear-disk being broken away. Fig. 13 is a side elevation of the same. Fig. 14 is a sectional elevation illustrating said modification. Fig. 15 is a top plan view of the pawl-disk employed in said modification. Fig. 16 is a fragmentary sectional view on about the line 16 45 of Fig. 15. Fig. 17 is a detail top plan view of the transmitting-gear carrier, the gears being indicated by dotted lines. Fig. 18 is a sectional elevation of the same, and Figs. 19, 20, and 21 are diagrammatic views

illustrative of the action of the item-indicator and the totalizer. In each of these views the full lines illustrate the positions of the parts at the end of the item-indicating movement and before the totalizing movement has commenced. The light dotted lines indicate the positions of the parts at the extreme limit of the totalizing movement, including the overthrow of the totalizer, and the heavy dotted lines indicate the position of the totalizer after it has receded from its overthrow movement. 50 Steps of movement of the item-indicator are represented by the light full vertical lines and the heavy dot-and-dash line, and steps of movement of the totalizer are represented by the light vertical dash-lines. 60 65

This invention relates to improvements in registers, and more particularly to billiard-registers, the mechanism being started at the beginning of the game and stopped at the completion of such game, the register then 70 showing the amount due from the players of the particular game just completed and also the total amount due for all games played upon the table in connection with which the register is employed. 75

One object of the present invention is to provide a register having a clock-train or other suitable driving mechanism and a totalizer which is manually operable, but whose operation is controlled by said clock-train, whereby although the clock-train controls the operation of the totalizer said clock-train is relieved of the work of operating the totalizer. 80

A further object is to provide a register having a clock-train or other suitable driving mechanism, an item-indicator driven by said clock-train, and a totalizer which is manually operable, but whose operation is controlled by said clock-train. 85

A further object is to provide a register 90 having a totalizer or other indicator adapted to indicate in definite multiples, the mechanism being so constructed that the indications will be in integral multiples notwithstanding the fact that the actual time of operation of the register may have been such that the indication corresponding to such time of operation should actually be a definite multiple and 95

a fraction, the amount indicated by the indicator being such definite multiple should the actual amount corresponding to the time of operation be such multiple plus one-half or 5 less of the unit and the indication being the next higher definite multiple should the time of operation have been such that the actual indication corresponding to such time would be such definite multiple and a fraction greater 10 than one-half.

A further object is to provide a register of the character indicated having an item-indicator and a totalizer, said totalizer being adapted to indicate its totals in definite multiples, the mechanism being such that the item-indicator indicates the actual amount due for 15 the time actually consumed in playing, while the totalizer indicates in definite multiples, it being possible to always reset the item-indicator to zero and to properly actuate the totalizer notwithstanding the fact that when brought to its position of final rest after resetting action of the item-indicator the said item-indicator and total-indicator may not 20 have been moved through distances exactly corresponding to each other, thus making it possible to fully reset the item-indicator, although the totalizer may disregard the fractions indicated by said item-indicator.

30 A further object is to provide a register of the character indicated whereby, although the indications are given in dollars and cents, the mechanism can be caused to indicate amounts due at various rates per hour.

35 A further object is to provide means whereby the resetting tool or key for operating the totalizer cannot be withdrawn until the item to be added into the machine has been so added.

40 A further object is to provide simple and convenient means for starting the mechanism and for placing the shutter of the totalizer wholly under the control of the proprietor.

To these ends and also to improve generally upon devices of the character indicated the 45 invention consists in the various matters hereinafter described and claimed.

Referring now more particularly to the drawings, 1 indicates a base-plate upon which the side walls of the casing 2 are properly 50 supported, and 3 is a suitably-supported dial within the casing, a glass plate or the like, 4, which forms the front of the casing, covering said dial. Suitably supported upon the base 1 within the casing is a clockwork mechanism 55 5 of any convenient construction, 6 being the usual minute-arbor of such mechanism and 7 being the customary balance-wheel. The dial is provided with a suitable scale indicating monetary amounts in definite multiples, (I have 60 found it convenient to provide the dial with a scale indicating amounts in multiples of five cents up to six dollars,) and a suitably-driven item-indicator 8 travels over the exposed face of the dial and co-operates with said scale. A 65 totalizer 9 has numbering-disks which are

adapted to be exposed through a slot in the dial, as is well understood, said slot being controlled by a shutter 10. A brake 11 controls the clockwork mechanism. The item-indicator is in frictional driving connection with the clock-train, and the totalizer is normally out of connection with the item-indicator and the clock-train. 70

When play is commenced, the brake 11 is thrown into position to release the balance-wheel, whereupon the clock mechanism drives the item-indicator during the time of play, and when play ceases the attendant inserts a tool or key, which throws the brake into braking position, whereupon the clockwork mechanism and its driven indicator come to rest, and also throws the totalizer into driving connection with the item-indicator. The item-indicator shows upon the scale the amount due for the particular time which has just been 85 consumed in play, and after this time has been noted by the attendant and the players the attendant further operates the tool, whereupon the item-indicator is restored to zero and the totalizer is operated to add into the 90 machine the item just indicated by the item-indicator. The operating-tool is then withdrawn; but the clockwork mechanism remains at rest until further manipulation. 85

Considering now the details of construction, 95 12 is a post or spindle suitably supported upon the base 1, and rotatably mounted upon this spindle and resting upon a shoulder 13 thereof is a sleeve 14, upon which the indicator 8 is mounted to rotate with said sleeve. Frictionally connected to the outer portion of said sleeve is a driving-gear 15. Fast upon the inner portion of the sleeve is a ratchet-disk 16, and fast upon said sleeve and intermediate 100 said driving-gear and said ratchet-disk is preferably mounted a peripherally-threaded outer sleeve 17. A driving-pinion 18 is carried by the usual minute-arbor 6 of the clockwork mechanism, and this pinion is in driving connection with said driving-gear 15. This connection is here shown as effected through a driving-gear 19, in mesh with said pinion 18 and mounted upon a suitable post or arbor 20, and a second gear 21, in mesh with said driving-gear 15 and connected to and carried by 110 115 said gear 19. It will thus be apparent that operation of the clockwork mechanism serves to drive the item-indicator 8. 110

The heretofore-mentioned frictional connection between the driving-gear 15 and the 120 item-indicator-carrying sleeve 14 can of course be effected in many ways. I prefer, however, for the sake of cheapness and simplicity to produce spring-fingers 22 upon the driving-gear, as by cutting slots 23 in the body portion of the spring-plate from which said gear 15 is produced, said slots opening upon and radiating from the central opening of said gear-plate, through which the sleeve 14 passes. These spring-fingers are oppositely deflected 125 130

and are then engaged between the outer sleeve 17 and the shoulder produced by a peripherally-projecting lip 24 upon said sleeve 14. Rotatably mounted upon said spindle 12 and 5 behind said ratchet-disk 16 is a sleeve 25, having a circumferential groove 26. Fixedly mounted upon the outer end of said sleeve 25 is a pawl-disk 27, whose pawls are adapted to coöperate with the ratchets of the before-mentioned ratchet-disk 16, and mounted upon the inner portion of said sleeve 25 and having sliding connection therewith is a sleeve 28, which has a gear 29 formed thereon. The sliding connection between the sleeves 25 and 28 is 10 conveniently produced by causing said sleeves to fit each other loosely and by dropping a pin 30 through apertures in both said sleeves, the inner end of the pin resting against a boss 31, formed upon the base 1, in which boss the 15 spindle 12 is seated and against which boss the inner ends of the sleeves 25 and 28 engage and the outer end of said pin being covered by the said ratchet-plate 27.

A shaft 32, journaled in suitable standards 20 25, which project from the base 1, has its inner end provided with a gear 34, which meshes with the before-mentioned gear 29, the counting-disks 35, 36, 37, and 38 of the totalizer being mounted upon this shaft between the 25 30 said standards 33. The particular totalizer herein illustrated forms no part of the present invention, but is fully shown and described in my previous application filed April 9, 1903, Serial No. 151,875, so that a detailed explanation 35 40 of said totalizer is unnecessary in this specification. It may be said, however, that the combined units and tens disk 38 is fast upon the said shaft 32, while the remaining counting-disks 35, 36, and 37 are loose upon 45 50 said shaft, the combined units and tens disk being driven directly by the shaft 32 and each higher disk being driven from its next lower disk through one of the transmitting-pinions 39. The outer end of the shaft 32 is adapted 55 60 to receive the totalizer-operating key or tool X, said shaft end conveniently having pins 40, adapted to enter recesses 41 in what may be termed the "inner" end of the said operating-tool. It will now be apparent that when 65 70 the shaft 32 is engaged and rotated by the operating-tool X the sleeve 25 and its carried pawl-disk 27 are correspondingly rotated. A yoke has its arms 42 at the sides of the totalizer and pivoted to one of the standards 33, 75 80 the inner free ends of said arms being bent inwardly to produce fingers 43, which lie in the before-mentioned circumferential groove 26 in the said sleeve 25. The connecting-piece 44 at the outer end of the yoke lies behind 85 90 the outer end of the said shaft 32 and is engaged by a compression-spring 45 between said connecting-piece and the base 1, whereby the inner end of the yoke is normally forced inwardly to hold the pawl-disk 27 out of engagement with the ratchet-disk 16. The said

connecting-piece 24 is preferably twisted slightly to produce an inclined surface 46, adapted to be engaged by the operating-tool X. Thus the pawl-disk 27 is normally out of engagement with the ratchet-disk 16, where- 70 by the driving-gear 15 is free to be driven by the clockwork mechanism and to thus drive the item-indicator 8. When, however, the operating-tool is inserted through the appropriate opening 47 in the casing and engages 75 the shaft 32, said tool also engages the cross-piece or connecting-piece 44 of the yoke and throws the inner end of the yoke outwardly against the action of the spring 45, thus bringing the pawl-disk 27 into engagement 80 with the ratchet-disk 16. Rotation of the operating-tool then serves to actuate the totalizer and also (through the pawl-disk and the ratchet-disk) to reset the item-indicator, the frictional connection between the driving-gear 15 and the sleeves 14 and 17 permitting 85 the item-indicator to be reset while the clock-train and the driving-gear 15 remain at rest. Upon withdrawal of the operating-tool the spring 45 rocks the yoke, and the pawl-disk 90 is thus carried into innermost position out of engagement with its coöperating ratchet-disk. The amount of rotation permitted the shaft 32, and consequently the extent of operation of the totalizer, is controlled by the item-indicator and is determined by the distance through which the item-indicator has been driven since the last operation of the totalizer. A pin or other suitable stop member 48 projects from the outer surface of the ratchet-disk 16, which in the operation of the machine always moves with the item-indicator, and an arm 49, which is pivotally connected to the lever-plate 50, lies in the path of resetting movement of said pin. Said plate 50 100 105 is pivotally supported upon one of the standards 33, and the extent of pivotal movement of said plate is limited in a manner to be hereinafter more fully explained. As the item-indicator is driven forwardly the stop-pin 48 moves away from the end of the coöperating stop-arm 49. When, however, the item-indicator is driven backwardly through the rotation of the totalizer-actuating shaft 32, the said stop-pin finally engages its coöperating stop-arm 49, and the parts are thus brought to rest after the plate 50 has been slightly rocked upon its pivot and has reached its limit of pivotal movement. The relationship 110 115 between the stop-pin 48, its coöperating stop-arm 49, and the item-indicator 8 is such that when the stop-arm 49 arrests the movement of the parts the said item-indicator stands at zero. Preferably provision is made whereby before the resetting action of the item-indicator is arrested said item-indicator must be moved backwardly through the same distance through which it has been advanced by the clock mechanism. One means of effecting 120 125 130

the body portion of the arm 68 rests upon a suitable projection 70 upon the lever-arm 62 and the lever-arm 64 is in the position heretofore indicated in the path of movement of 5 the operating-tool X. As said tool is inserted into the machine it rocks the lever including the arms 62 and 64, as heretofore indicated, thus braking the clockwork mechanism, and this rocking movement is sufficient to carry 10 the lug or projection 70 out of supporting position under the body portion of the arm 68, the finger 69 then falling to rest upon said lug, and inward movement of the lever-arm 62 sufficient to carry the brake out of braking relation to the balance-wheel 7 is prevented by 15 reason of the fact of said lever-arm 68 lying in the path of such inward movement of said lug or projection 70. When said lever including the arms 62 and 64 is in this position, 20 the free end of its arm 64 lies in rear of the before-mentioned shoulder 65 upon the operating-tool, so that withdrawal of said tool is impossible. As the shaft 32 is rotated, however, and the stop-pin 48 when almost at 25 its position of rest engages the co-operating stop-arm 49, said stop-pin throws said stop-arm backwardly until the movement of said stop-arm is arrested by reason of the engagement of the arresting-pawl 52 with the 30 counting-disk 38, and this backward movement of the stop-arm rocks the lever-plate 50 sufficiently to cause the end of the arm 68 to engage the said lug or projection 70 and rock the bell-crank lever 71 (which includes the said arms 62 and 64) sufficiently to 35 carry the free end of the said arm 64 out of the path of movement of the said shoulder 65, whereupon the operating-tool is free to be withdrawn from the casing. It is to be noted, 40 however, that the said arm 64 is not thrown out of position to obstruct the withdrawal of the operating-tool until the item-indicator is brought to zero position and the resetting of the item-indicator, together with the adding 45 of the last item in the totalizer, have been completed. Manifestly, when the item-indicator is at zero position, with the lever 71 and the arm 68 in the positions last indicated, the lever-arm 62 is in substantially its extreme rearward position and the brake 11 is in braking 50 engagement with the balance-wheel 7, so that the withdrawal of the operating-tool X does not serve to start the clockwork mechanism. A rod 72, pivotally connected with said arm 55 68, depends from said arm and has a bent end 73, which lies adjacent the keyhole 74 through the casing, so that said bent end can be engaged by the bit 75 of an appropriate key Y, the movement of the key thus serving to elevate the rod 72 and carry the end of the body portion of the arm 68 out of the path of the lug or projection 70, whereupon the spring 66 asserts itself and rocks the lever 71 sufficiently to throw the brake 11 out of braking engagement with the balance-wheel 7.

The shutter 10 controls the dial-slot, through which the totalizer can be read, said shutter being slidable upon the ends of the before-mentioned standards 33 and having a rod 76 depending therefrom and provided with a bent 70 end 77, which lies adjacent the before-mentioned keyhole 74, so that the bit 78 of a key Z can engage said bent end 77, and thus elevate the shutter into unobstructing position when the key is properly turned, the shutter 75 falling by gravity into obstructing position when the bit is moved away from said bent end 77, all as will be readily apparent. Each key Y and Z is provided with the usual longitudinal opening in its end and adapted to 80 receive the guide-post 78^a, and each key is adapted to be inserted through the keyhole 74; but the key Y can operate only the mechanism for starting the clockwork, while the key Z can operate only the shutter. The key 85 Y being in the possession of the attendant, he and he only can permit operation of the register, and the key Z being in the possession of the proprietor he and he only can operate the shutter, and thus consult the totalizer. 90 Within the casing is an obstructing-plate 79, which is provided with a keyhole 80 in alignment with but smaller than the before-mentioned keyhole 74. The bent end 77 of the shutter-actuating rod 76 lies intermediate the 95 front of the casing and said obstructing-plate 79, while the bent end 73 of the starting-mechanism rod 72 lies behind the said obstructing-plate 79. The bit of the key Z is so wide that while it can pass through the keyhole 74 it 100 cannot pass through the keyhole 80. Thus said key Z can operate the shutter, but cannot reach the bent end 73 of the arm 72. On the other hand, the bit 75 of the key Y is narrow enough to pass through the keyhole 80 as 105 well as the keyhole 74 and to thus obtain access to the bent end 73, but said bit 75 is, as shown by dotted lines in Fig. 7, of greater length than is the distance between the obstructing-plate 79 and the casing-plate, so that said key 110 Y cannot be turned until its bit has been forced inwardly beyond the obstructing-plate 79.

I have hereinbefore referred to the fact that the totalizer can disregard fractions, although the item-indicator can be fully restored to its 115 zero position. The totalizer is driven directly by the shaft 32, while the item-indicator is reset by the action of one of the pawls upon the pawl-plate 27 when in engagement with one of the ratchets of the ratchet-plate 120 16. If the net movement of the totalizer corresponds exactly with the resetting movement of the item-indicator, it will be manifest that the totalizer will add into the machine a number exactly corresponding to the item represented by the distance through which the item-indicator is moved in its resetting movement. If, however, the net movement of the totalizer be less than the resetting movement of 125 the item-indicator, the totalizer will add int 0

the machine a number less than the item represented by the distance through which the item-indicator is driven when being reset, and if the net movement of the totalizer be greater than the movement of the item-indicator when the latter is being reset the totalizer will add into the machine an amount greater than the item corresponding to the space through which the item-indicator is moved in being reset. Bearing these facts in mind, the operation of the mechanism now to be described will be clear.

As has been heretofore indicated, the arresting-pawl 52 has a slot 53, which receives the pivot-shaft 51, so that even after this arresting-pawl has been engaged by a tooth of the counting-disk 38, as shown by the light dotted lines in Fig. 6, the said arresting-pawl can move a limited distance in a line transverse said shaft 51. In the present mechanism this movement thus permitted the counting-disk is equal to one-half of a step of said disk, one step of the disk being the distance through which the disk must move in order to bring a next succeeding higher number into position to be exhibited through the sight-slot in the dial. Therefore in the present register the totalizing mechanism is permitted to have an overthrow not to exceed one-half of a step. The before-mentioned spring 56 serves to return the counting-disk 38 after its overthrow.

As a special pawl-and-ratchet construction is illustrated in the remaining figures of the drawings, although the operation now under consideration can be effected by a pawl and ratchet of ordinary construction, reference is now made to the diagrams shown in Figs. 19, 20, and 21 in order that the construction and operation now being described may not be confused because of the said special pawl-and-ratchet construction. Referring now more particularly to the said diagrams, the totalizer is represented as a straight plate *m*, controlled by the locking-dog 59, while *n* indicates the effective pawl, this pawl in the diagrams being shown as integral with the totalizer-plate, for the reason that the totalizer and the pawl-plate 27 move together. The ratchet-plate 16 is also shown as a straight plate with the item-indicator 8 integral therewith, the stop-pin 48 being shown upon this ratchet-plate and the stop-arm 49 being also indicated. The dial 3, with which the item-indicator coöperates, is also shown as a straight plate. The dotted line *o* indicates the line of the sight-opening through which the totalizer is read, and the dot-and-dash line *v* indicates the zero position of the hereinafter-mentioned tooth *s*. With the exception of the particular construction of the elements the description about to be given applies as well to the mechanism illustrated in other views of the drawings as to the mechanism shown in the said diagrams.

65 As the totalizer expresses its results in mul-

tiples of five and the scale with which the item-indicator coöperates has its divisions representing multiples of five, five will be considered the unit, the numbers upon both the totalizer and the scale for the item-indicator being integral multiples of this unit. The parts are so constructed and arranged that when the item-indicator points directly to one of these integral multiples of the unit one of the ratchet-teeth of the ratchet-plate 16 is coincident with the position occupied by a ratchet-tooth of said plate when the said plate and its carried item-indicator 8 are in zero or reset position, while the effective pawl *n*, which moves directly with the totalizer, lies one-half a step in advance of said first-mentioned tooth of the ratchet-plate, a step as herein considered being the distance between one division of the item-scale and its next division, the distance through which the item-indicator must move when passing from one of such divisions to the next, and also the distance through which the totalizer must move in order to pass from the position at which one number is exposed to the position at which the next number is exposed.

Fig. 19 shows the elements in their proper positions after the item-indicator has traveled through a space equal to two steps, such space representing ten cents upon the dial indicated. 95 When the parts are in this position, the tooth *r* is a half-step in advance of the pawl *n*, (i. e., upon the side of the pawl *n* toward which said pawl moves forwardly,) and said tooth *r* is also coincident with the position which the tooth *s* occupies when the item-indicator 8 is in reset position. The stop-pin 48 has moved from its zero position a space equal to that through which the item-indicator 8 has moved and through which the tooth *r* has advanced, 105 and in this instance this space is two steps. To reset the item-indicator and to operate the totalizer, the totalizer is moved forwardly, as has been previously described, the pawl *n* engages the tooth *r* after the totalizer has moved through half a step, and the totalizer then continues its forward movement until arrested by reason of the stop-pin 48 being arrested by the stop-arm 49; this arresting of the stop-pin by the stop-arm occurring after the item-indicator has been moved through two steps. As the totalizer had a half-step of movement before engaging the tooth *r* and then had two steps of movement after engaging said tooth, when the item-indicator 8 has been brought 110 to zero the totalizer will have moved through two and one-half steps and will be in the position indicated by the light dotted lines, in which position the character "10" will be a half-step in advance of the sight-opening, as 115 shown by the middle row of figures upon the totalizer in said diagrams. As has been previously described the spring 56 returns the totalizer through a half-step after the totalizer has been thrown to the limit of its movement, 120 125 130

and this returning of the totalizer will cause the desired number "10" to be brought into line with the sight-opening, as shown by the upper row of figures in Fig. 19 of the diagrams, this final position of the totalizer being indicated by the heavy dash-lines. Suppose, however, that the item-indicator has advanced an integral number of steps plus a fraction of a step less than a half—*e. g.*, suppose that the item-indicator has advanced to "12 cents," as illustrated in Fig. 20 of the diagrams. In such event the tooth *r* will have advanced beyond the zero position of the tooth *s* a distance equal to the fraction of a step last above referred to. This fraction is less than a half-step, and as the pawl *n* is a half-step from said zero position of the tooth *s* said tooth *r* will lie upon the forward side of said pawl. Therefore when the totalizer moves forwardly to indicate its total and to reset the item-indicator a portion of the first half-step of the totalizer will be employed in bringing the tooth *r* to the zero position of the tooth *s*. The totalizer will then move forwardly until arrested by reason of the stop-pin 48 being arrested by the stop-arm 49, (whereby the item-indicator is brought to zero,) and the totalizer will then be returned through a half-step. One half-step of forward movement of the totalizer is ineffective so far as the totalizing is concerned, for the totalizer is returned through such half-step. Therefore when the tooth which is to be engaged by the pawl *n* is less than a half-step from the zero position of the tooth *s* and is thus between the pawl *n* and said zero position of the tooth *s* that portion of the movement of the totalizer necessary to bring said tooth *r* to the zero position of the tooth *s* is ineffective so far as the totalizing is concerned, and the movement of the totalizer which is effective is merely the movement from the zero position of the tooth *s* to the zero position of the tooth *r*, so that whenever the item-indicator has advanced an integral number of steps plus a fraction of a step less than one-half the totalizer will serve to reset the item-indicator to zero position; but the only amount which will be added into the totalizer will be the said integral number of steps, the fraction of a step being disregarded. Suppose, however, that the item-indicator has advanced through a space equal to an integral number of steps plus a fraction of a step greater than one-half, as shown in Fig. 21 of the diagrams, this figure showing the item-indicator advanced to indicate "13 cents." In this case the tooth *r* (which is the tooth engaged by the pawl for adding ten cents) will have advanced past the pawl *n*, so that when said pawl *n* advances to effect resetting it must engage the tooth *u*. After the pawl *n* in its totalizing and resetting action has moved into engagement with the tooth *u* the totalizer will of course have a movement equal to the number of steps and fraction of a step which the stop-pin 48 has moved away from zero position in engagement with the stop-arm 49, so that the totalizer is thus enabled to have a movement corresponding to the full space 70 through which the item-indicator has advanced; but the first half-step of movement of the totalizer brings the pawl *n* merely to the zero position of the tooth *s*, and the tooth *u* is before the resetting action of the item-indicator has commenced spaced from said zero position of the tooth *s* a distance which is equal to one step less than that fraction of a step through which the item-indicator has advanced. In other words, even after the totalizer has moved through its first half-step of movement it must also before the pawl *n* can engage the tooth *u* move through a distance which when added to the fraction of a step through which the item-indicator has advanced 75 will equal a whole step. The item-indicator has been advanced an integral number of steps plus a fraction of a step greater than a half. The movement of the totalizer will be one-half step plus that fraction of a step which when 80 added to the last-mentioned fraction will make a whole step plus said integral number of steps and the fraction of a step through which the item-indicator has been advanced minus one-half step. A half-step of this movement being 85 both added and subtracted, such half-step can be disregarded so far as the totalizing action is concerned, and, as will be readily apparent, the remaining movement of the totalizer will be an integral number of steps one greater 90 than the integral number of steps through which the item-indicator was advanced, so that should the item-indicator be advanced an integral number of steps plus a fraction of a step greater than a half the totalizer will reset the item-indicator and will add into the machine an amount corresponding to an integral number of steps one greater than the integral number of steps through which the item-indicator was advanced. Therefore if 95 the item-indicator, for example, indicates ten, eleven, or twelve cents the movement of the totalizer will serve to reset the item-indicator to zero, but will add only ten cents into the totalizer. If, however, the item-indicator has 100 been advanced to thirteen or fourteen cents, the movement of the totalizer will serve to reset the item-indicator to zero and will also serve to add fifteen cents into the totalizer. I have said that when the item-indicator has 105 been advanced an integral number of steps plus a fraction of a step greater than a half the distance which the tooth *u* lies behind the zero position of the tooth *s* will be that fraction of a step which when added to the last 110 above-mentioned fraction of a step will equal a whole step. To prove this, it is only necessary to remember that the said fraction of a step through which the tooth *r* has advanced is that portion of a step which said tooth *r* 115

lies in advance of the zero position of the tooth *s*. The distance between the tooth *r* and the tooth *u* is one step. Therefore as this one step is composed of the distance between the tooth *r* and said zero position of the tooth *s* plus the distance between the tooth *u* and said zero position of the tooth *s* and as said distance of the tooth *r* from the said zero position of the tooth *s* is the said fraction of a step through which the item-indicator has advanced the distance between the tooth *u* and said zero position of the tooth *s* must be that fraction of a step which when added to the said fraction of a step through which the item-indicator has advanced will equal a whole step.

It will of course be apparent that the distance which the pawl *n* lies from the zero position of the tooth *s* will determine the action of the totalizer. As herein illustrated, said pawl *n* lies one-half step from the zero position of the tooth *s*, so that any fraction of a step less than a half will be disregarded by the totalizer, while any fraction of a step greater than a half will be added into the totalizer as a whole step. Should said pawl *n* be only one-third of a step from the zero position of the tooth *s*, any fraction of a step less than a third would be disregarded by the totalizer, while any fraction greater than a third would be added into the totalizer as a whole step.

I have heretofore said that the slot 53 of the arresting-pawl 52 permits the before-mentioned overthrow of the totalizer. Of course the said slot 53 could be of such length that upon the completion of the desired overthrow the upper wall of the slot would engage the said shaft 51, and thus bring the arresting-pawl 52 to rest. In the herein-illustrated embodiment of my invention, however, the pawl-disk 27 is connected to the shaft 32 through gears 29 and 34, and as gear-teeth are apt to wear it is possible that after the mechanism has been in use for some time there may be so much lost motion between the ratchet-disk 16 and the shaft 32 that if the upper wall of the slot 53 were depended upon to arrest the movement of the arresting-pawl 52 transverse to the shaft 51 the overthrow given the totalizer might become excessive. Therefore I prefer to employ an adjustable stop for the said arresting-pawl, said stop being here shown as a wedge 81, slidable upon the base 1 and slotted, as at 82, to receive a set-screw 83, which is seated in a suitably-threaded opening in said base 1.

The present mechanism can be readily adjusted to cause it to register amounts at any desired rate per hour. The scale upon the dial is, as has been previously indicated, provided with divisions indicating monetary amounts. If the rate per hour charged by the keeper of the billiard-table be sixty cents, then the item-indicator must be moved at such

a speed that in one hour it will travel the distance between a given scale-division and the scale-division sixty cents greater than said given scale-division. Should the rate per hour be less than sixty cents, the rate of travel of the item-indicator must be correspondingly lowered. The arbor 6 of the clockwork mechanism moves, of course, at a uniform rate of speed; but the gear 15, which drives the item-indicator, is driven from said arbor 6 through the interposed gears 19 and 21, the gear 19 meshing with the gear 18 upon said arbor 6 and the gear 21 meshing with the gear 15. The rate of travel of the gear 19 is constant; but if the size of the gear 21 be changed the rate of travel of the gear 15 (and consequently of the item-indicator) will be correspondingly changed. The before-mentioned post 20, upon which the gear 19 is mounted, is carried by a swinging plate 84, which is pivoted about the before-mentioned arbor 6, said plate being provided with a segmental slot 85, through which extends a set-screw 86, which engages a threaded opening in the outer plate 87 of the clockwork mechanism. Therefore notwithstanding the diameter of the gear 21 the plate 84 can be so swung upon its pivot (the arbor 6) that the gear 21 can be thrown into mesh with the gear 15, and as the post 20 in the various movements of the plate 84 always moves in a line concentric with said arbor 6 the gear 19 is of course always in mesh with the gear 18. The gear 21 can of course be removably secured to the gear 19 in any convenient manner. I have here shown the said gear 21 as provided with pins 88, adapted to fit the corresponding openings in the gear 19, so that to connect the gears 21 and 19 it is only necessary to place the gear 21 upon the gear 19 with the said pins in the said openings. A headed screw 89, entering a threaded socket in the end of said post 20, has its head extending over the said gear 21, and thus prevents the gears from becoming separated from each other and from the post.

Manifestly many forms of pawls and ratchets can be employed between the sleeve 14 and the sleeve 25. Because of their simplicity and cheapness of construction I prefer, however, to employ the plates illustrated particularly in Figs. 2, 3, and 5. As here shown, the ratchet member comprises simply a disk which is slit radially at its periphery to produce the tongues 90, and these tongues are merely twisted slightly, as best shown in Fig. 2, the result being a disk provided at its periphery with a series of ratchet-teeth. The pawl member is simply a disk which has near its periphery a series of elongated slots 91, which are substantially concentric with the center of rotation of the disk, each of these slots opening at one end into a slot 92, which opens upon the periphery of the disk. This leaves fingers 93, 94, 95, and 96 connected at one end to the body portion of the pawl-disk,

and as the pawl-disk is made of resilient material and the fingers are bent upwardly (i.e., toward the ratchet-plate) at their free ends said fingers form resilient pawls.

5 As will be apparent from an inspection of the diagrams heretofore referred to and constituting Figs. 19, 20, and 21, it is necessary in order to effect the desired relationship between the pawl *n* (which moves with the totalizing mechanism) and the tooth connected to the item-indicator (which said tooth is to be engaged by said pawl in the totalizing and resetting movement given the totalizer) that for each division of the item-scale there be 10 some member adapted to move with the item-indicator and so related to the totalizer-driven pawl which is to engage such member that when the item-indicator comes to rest this member will bear the desired relationship to 15 the actuating-pawl, such relationship being indicated in the said diagrams. This could be readily effected were the totalizer to have a single actuating-pawl movable therewith and the item-indicator to have connected 20 thereto a ratchet-disk having as many teeth as there are divisions of the item-indicator scale. It has been found convenient, however, to provide the item-indicator scale with one hundred and twenty divisions. Mani- 25 festly a ratchet-plate having one hundred and twenty teeth must be quite large or the teeth must be very small, and, furthermore, the expense of a ratchet-plate is increased by increasing the number of teeth which must be 30 provided thereon. Therefore, for the sake of economy of space and of cheapness of manufacture, I prefer to employ a ratchet-plate having less teeth than there are divisions upon the item-scale. In the embodiment of my 35 invention illustrated in the first eleven figures I have shown the ratchet-disk as provided with thirty teeth 90. There are, however, four pawls 93, 94, 95, and 96, adapted to coöperate with these teeth. The ratchet- 40 teeth are, of course, all of the same width. One of the pawls (the pawl 93 in Fig. 5) is, of course, adapted in a certain position of the ratchet-plate to lie coincident with the surface of a ratchet-tooth, so that this 45 pawl would immediately engage the ratchet-tooth upon movement of the pawl. Another pawl (the pawl 94) lies behind the line of a tooth a distance equal to one-quarter of the space from one tooth to the next. Another 50 pawl (the pawl 95) lies in rear of a tooth a distance equal to one-half of the space between teeth, and the remaining pawl (96) lies in rear of a tooth a distance equal to three-fourths of the space between teeth. Therefore at each 55 portion of a revolution of the ratchet-plate equal to one-quarter of the space between teeth of said ratchet-plate some tooth of the ratchet-plate will be in position to be engaged by a pawl in the manner indicated in the be- 60 fore-mentioned diagrams—for example, as

shown in Fig. 5, the pawl 93 is ready to engage a ratchet-tooth. In order to carry the item-indicator from one scale-division to the next succeeding scale-division, the ratchet-disk will move through one one-hundred-and-twenty-fifth of a revolution, and as there are thirty teeth in the ratchet-disk this one one-hundred-and-twenty-fifth of a revolution will equal one-quarter of the space between teeth upon the ratchet-disk. Should the ratchet-disk be advanced from the position shown in Fig. 5 this one one-hundred-and-twenty-fifth of a revolution, so that the item-indicator would be advanced one scale-division, the ratchet-tooth 90^b would, of course, move through a distance 70 equal to one-quarter the distance between teeth and would, therefore, be in position to be properly engaged by the pawl 94 notwithstanding the fact that the tooth 90^a would have advanced too far to be properly engaged by 75 the pawl 93. Should the ratchet-disk then advance through another one-hundred-and-twenty-fifth of a revolution by reason of the item-indicator having been advanced another scale-division, the tooth 90^c would be so advanced 80 as to be in position to be properly engaged by the pawl 95, while should the ratchet-disk be advanced through another one-hundred-and-twenty-fifth of a revolution the tooth 90^d would be in position to be properly engaged by the 85 pawl 96. An advance of another one-hundred-and-twenty-fifth of a revolution would be sufficient to bring the tooth 90^e in position to be properly engaged by the pawl 93, and so on. Therefore a ratchet-plate having less teeth 90 than there are divisions of the item-scale can be employed in the present mechanism if there be employed with this ratchet-plate the proper 95 number of pawls which are related to the teeth of the ratchet-plate and to each other in the 100 manner just described.

In Figs. 12 to 16 I have illustrated certain modifications. In these views the spindle 12, the gear 15, the sleeve 14, the gear-sleeve 28, the base 1, the totalizer-shaft 32, with its gear 110 34, the lever-plate 50, the standards 33, and the yoke-arms 42 are the same as heretofore described. The connecting-piece 44^x, however, is inclined in an opposite direction to the inclination of the before-mentioned connecting-piece 44 and lies upon the outer side of the tool-receiving end of the shaft 32. Connected to the inner end of the sleeve 14 to rotate with said sleeve is a ratchet-plate 16^x, 115 the teeth of this ratchet-plate being shown as 120 of the usual construction and not of the special construction shown upon the ratchet-plate 16, and this ratchet-plate 16^x is preferably held properly spaced from the gear 15 by means of a distance-piece 97. In the outer 125 face of said ratchet-plate 16^x is a spiral groove 98, which corresponds generally to the before-mentioned peripheral thread upon the sleeve 17. The stop-arm 49^x, which is pivoted to 130 the lever-plate 50 in the same manner as the

heretofore-described stop-arm 49, is provided at its free end with a pin 99, which rests in the before-mentioned spiral groove 98. The said distance-piece has a projection 48^x, which 5 forms a stop member adapted to engage the free end of the stop-arm 49^x in the same manner in which and for the same purpose for which the projection 48 engages the stop-arm 49. The office of the spiral groove 98 and 10 the pin 99 is to carry the free end of the stop-arm out of the path of movement of the stop or projection 48^x, just as the thread upon the sleeve 17 carries the free end of the stop-arm 49 out of the path of movement of the stop-pin 48. The gear-sleeve 28 is fastened to an 15 inner sleeve 100, which is rotatably mounted upon the before-mentioned spindle 12 and carries the pawl-disk 27^x at its outer end. Slidable upon said inner sleeve 100 is a sleeve 101, which is non-rotatable and has the inner ends 20 of the yoke-arms 42 connected thereto, as clearly shown in Figs. 13 and 14. At its outer end this sleeve 101 has an annular inclined wedge portion 102. The pawl-plate 25 27^x has radial slots 103, in each of which travels a rib 104 upon a slidable plate 105, each of these plates being held upon the pawl-plate by a back plate 106, suitably connected to the rib 104 and projecting beyond the sides 30 of said rib, as illustrated in Fig. 16. Each slidable plate 105 carries a projecting pawl-tooth 107, said teeth when the parts are assembled lying at the periphery of the ratchet-plate 16^x and being adapted to engage the 35 teeth upon the periphery of said ratchet-plate. Springs 108 tend to throw said pawl-teeth 107 into engaging position; but said pawl-teeth are normally held out of such engaging position against the tension of said springs 108 by 40 reason of the fact that the spring 45^x normally holds the yoke-arms 42 in such position that their inner ends are in outer position, whereby the wedge portion 102 of the sleeve 101 lies in engagement with and between fingers 109 upon 45 the before-mentioned plates 106, this wedging action serving to move and hold the pawl-teeth 107 away from the teeth upon the ratchet-plate 16^x in a manner which will be apparent. Thus the ratchet-plate 16^x can be driven forwardly 50 with the item-indicator free from the pawls 107. When, however, the operating-tool X is inserted, it rocks the yoke in a manner which will be readily understood and carries the wedge-sleeve 101 away from the fingers 109, 55 whereupon the springs 108 assert themselves and the pawls are forced into engagement with the ratchet-disk 16^x. Rotation of the shaft 32 then causes the pawl-plate 27^x to rotate the ratchet-plate 16^x in a manner which will be 60 readily apparent, the pawls 107 being again thrown into disengaging position when the operating-tool X is withdrawn. In this modified construction the ratchet-plate 16^x is shown as provided with sixty teeth, this number of 65 teeth being one-half of the number of divisions

of the item-scale. Therefore in order to effect the totalizing and resetting operations here- 70 tofore described it is only necessary to provide two pawls, these pawls being so related to each other that when one of them is in po- sition to engage a ratchet-tooth, as shown in Fig. 12, the other lies midway between ratchet-teeth.

I am aware that minor changes in the construction, arrangement, and combination of 75 the several parts of my device can be made and substituted for those herein shown and described without in the least departing from the nature and principle of my invention.

Having thus described the invention, what 80 is claimed as new, and desired to be secured by Letters Patent, is—

1. In a register, the combination with an item-indicator, a motor for driving said item-indicator a predetermined distance in a given 85 time, means for resetting the item-indicator independently of the motor, and a totalizer operated to successively accumulate the items upon the successive operations of the resetting means, substantially as described. 90

2. In a register, the combination with an item-indicator, a clock mechanism in driving connection therewith, means for releasing the driving mechanism whereby the indicator indicates the monetary amount to be paid for 95 the time consumed in the travel of the indicator, a totalizer, and means for operating the totalizer and at the same time resetting the item-indicator, the totalizer being controlled and operated proportionately to the resetting 100 movement of the item-indicator, substantially as described.

3. In a register, the combination of a clock mechanism constituting a power-motor, a resettable item-indicator, means whereby said item-indicator is driven in one direction by said motor but has resetting movement independent of said motor, a totalizer normally out of driving connection with said motor and said item-indicator, and means whereby said 105 totalizer can be thrown into driving connection with said item-indicator, whereby said totalizer and said item-indicator can move together in the resetting movement of the latter; substantially as described. 110

4. In a register, the combination with a totalizer, and a resettable item-indicator having forward movement independent of said totalizer, a clock mechanism constituting a power-motor in driving connection with said item-indicator of means whereby said item-indicator can have resetting movement only upon movement of said totalizer, and means for operatively connecting said totalizer and said item-indicator whereby said item-indicator is 120 given resetting movement upon movement of said totalizer; substantially as described. 125

5. In a register, the combination with a totalizer and a resettable item-indicator having resetting movement only upon movement of 130

said totalizer, a clock mechanism constituting a power-motor in driving connection with said item-indicator of driving connection between said item-indicator and said totalizer, said driving connection including a clutch, means for throwing said clutch into and out of clutching relation, and means whereby said totalizer can be actuated only after said clutch has been thrown into clutching relation; substantially as described.

6. In a register, the combination with an item-indicator, and a totalizer, a clock mechanism constituting a power-motor in driving connection with said item-indicator of a clutch member connected to said item-indicator and movable therewith, a gear, driving connection between said gear and said totalizer, and a second clutch member in driving connection with said gear and having movement with respect to said gear toward and away from said first-mentioned clutch member; substantially as described.

7. In a register, the combination with an item-indicator, and a totalizer, a clock mechanism constituting a power-motor in driving connection with said item-indicator of a clutch member connected to said item-indicator and movable therewith, a spindle, a gear mounted upon said spindle, driving connection between said gear and said totalizer, and a second clutch member mounted upon said spindle and in driving connection with said gear, said second clutch member having movement with respect to said gear toward and away from said first-mentioned clutch member; substantially as described.

8. In a register, the combination with a totalizer, of a spindle, an item-indicator mounted upon said spindle, a clutch member connected to said item-indicator and movable therewith, a gear mounted upon said spindle, driving connection between said gear and said totalizer, a sleeve mounted upon said spindle and in driving connection with said gear but 40 substantially as described.

45

8. In a register, the combination with a totalizer, of a spindle, an item-indicator mounted upon said spindle, a clutch member connected to said item-indicator and movable therewith, a gear mounted upon said spindle, driving connection between said gear and said totalizer, a sleeve mounted upon said spindle and in driving connection with said gear but substantially as described.

9. In a register, the combination with an item-indicator, and a totalizer, of driving connection between said item-indicator and said totalizer, said driving connection including a clutch, a tool-actuated driving-shaft for said driving connection, and means whereby said clutch is thrown into clutching relation upon the application of the actuating-tool to said driving-shaft; substantially as described.

10. In a register, the combination with an item-indicator, and a totalizer, of driving connection between said item-indicator and said totalizer, said driving connection including a clutch, a tool-actuated driving-shaft for said driving connection, and a movable clutch-shifting element having a portion in proximity to said shaft, whereby in the application

of the tool to said shaft, said tool engages and moves said clutch-shifting element; substantially as described.

11. In a register, the combination with an item-indicator, and a totalizer, of driving connection between said item-indicator and said totalizer, said driving connection including a clutch, a tool-actuated driving-shaft for said driving connection, and a lever connected to said clutch for shifting the latter and having a portion in proximity to said shaft, whereby said lever portion is engaged and moved by the tool during the application of said tool to the shaft; substantially as described. 75

12. In a register, the combination with an item-indicator, of a standard, a tool-actuated shaft mounted in said standard, counting-disks mounted upon said shaft, driving connection between said item-indicator and said shaft, said driving connection including a clutch, and a yoke having its arms pivoted to said standard and connected to said clutch for operating the latter, the connecting portion of said yoke being in proximity to said shaft, whereby it is engaged and moved by the tool during the application of said tool to said shaft; substantially as described. 80 85 90

13. In a register, the combination with a continuously-operable motor which operates at a substantially uniform rate of speed, of a scale having divisions with designations of monetary amounts, an indicator movable along said scale and coöperating therewith, and means for causing said indicator to coöperate with said scale to indicate amounts due for a given time at various rates per given unit of time, said means including mechanism whereby said uniformly-operating motor can drive said indicator along said scale at different predetermined rates of speed; substantially as described. 95 100 105

14. In a register, the combination with a driving mechanism including a gear, of an indicator, a gear in driving connection with said indicator, a post movable in a line concentric with said first-mentioned gear, a gear supported upon said post, and a removable gear in driving connection with said post-supported gear and with said gear connected to said indicator; substantially as described. 115

15. In a register, driving mechanism including a gear, an item-indicator, a gear connected to said item-indicator, a post having movement concentric with said first-mentioned gear, a gear supported upon said post and meshing with said first-mentioned gear, and a gear concentric with said post-supported gear and removably connected to the same, said removable gear being in mesh with said gear connected to said indicator; substantially as described. 120 125

16. In a register, a driving mechanism including an arbor, and a gear upon said arbor, an item-indicator, a gear connected to said item-indicator, a plate pivoted upon said arbor, 130

a gear mounted upon said plate and meshing with said first-mentioned gear, and a gear removably connected to said plate-carried gear and meshing with said gear connected to said 5 indicator; substantially as described.

17. In a register, the combination with a clockwork mechanism, of an indicator whose operation is controlled thereby, a key-actuated part in driving connection with said indicator, a key for said part, a brake for said clockwork mechanism, and a movable brake-actuating member connected to said brake and in the path of movement of the key toward said key-actuated part, whereby in the application of said key to said key-actuated part said brake-actuating element is engaged by said key and moved by the same; substantially as described.

18. In a register, a clockwork mechanism, 20 an indicator whose operation is controlled by said clockwork mechanism, a key-actuated part for driving said indicator, a key for said part, a lever, a brake for said clockwork mechanism and connected to one arm of said lever, 25 and a second arm included in said lever and in proximity to said key-actuated part, whereby in the application of the key to said key-actuated part, said second arm of said lever is engaged by the key and said lever is thus moved; 30 substantially as described.

19. In a register, a clockwork mechanism, an indicator whose operation is controlled by said mechanism, a brake for said mechanism, a movable arm carrying said brake, and a 35 locking-arm coöperating with said first-mentioned arm for holding the same in brake-applying position; substantially as described.

20. In a register, a clockwork mechanism, an indicator whose operation is controlled 40 thereby, a brake for said clockwork mechanism, a movable arm carrying said brake, a locking-arm adapted to lock said movable arm in brake-applying position, means whereby when said brake-carrying arm is in brake-releasing position said locking-arm is also in releasing position, and means whereby when said brake-carrying arm moves into brake-applying position, said locking-arm moves into locking position; substantially as described.

21. In a register, a clockwork mechanism, an indicator whose movement is controlled thereby, a brake for said clockwork mechanism, a movable arm carrying said brake, a 55 projection upon said movable arm, a locking-arm, and a finger extending from said locking-arm whereby a shoulder is produced adapted to coöperate with said projection upon said brake-carrying arm, said parts being so portioned and arranged that when said brake-carrying arm is in brake-applying position said finger rests upon said projection and said shoulder is in the path of movement of said projection, while when said brake-carrying 60 arm is in brake-releasing position said lock- 65

ing-arm rests upon said projection and said projection is upon the side of said shoulder opposite that side upon which said projection lies when said brake-carrying arm is in brake-applying position; substantially as described. 70

22. In a register, an indicator, a key-actuated part for driving the same, a movable key-locking element for locking an inserted key against withdrawal, an engaging member having connection with said key-locking element, 75 and a coöperating engaging member movable with said indicator and, in the respective movements of said indicator, moving into and out of engagement with said first-mentioned engaging member; substantially as described. 80

23. In a register, a clockwork mechanism, an indicator coöperating therewith, a brake for said clockwork mechanism, a key-actuated part for driving said indicator, a key for said part, a movable key-locking element for preventing withdrawal of the inserted key, a lock for said brake, and operative connection between said indicator and said key-locking element, said operative connection including said brake; substantially as described. 85 90

24. In a register, a clockwork mechanism, an indicator coöperating therewith, a key-actuated part for driving said indicator, a key for said part, a movable key-locking element for preventing withdrawal of the inserted key, 95 a brake for said clockwork mechanism, connection between said key-locking element and said brake, a locking-arm adapted to lock said key-locking element in position to hold said brake in braking position, and connection between said indicator and said locking-arm for moving said locking-arm to throw said key-locking element into key-releasing position; substantially as described. 100

25. In a register, a clockwork mechanism, a 105 brake therefor, an indicator coöperating with said clockwork mechanism, a key-actuated part for driving said indicator, a lever one of whose arms forms a key-lock to prevent withdrawal of an inserted key, connection between 110 said brake and the other arm of said lever, a locking-arm movable into and out of position to lock said lever in brake-applying position and also movable in a line to rock said lever upon its pivot to cause said key-locking arm 115 to be thrown into key-releasing position, and means whereby said indicator serves to move said locking-arm in said direction to rock said lever; substantially as described.

26. In a register, a clockwork mechanism, a 120 brake therefor, an indicator coöperating with said clockwork mechanism, a key-actuated part for driving said indicator, a key for said part, a movable key-locking element for preventing withdrawal of the inserted key, connection between said key-locking element and said brake, a movable plate, a locking-arm 125 movably connected to said plate and having movement upon said plate into and out of position to lock said key-locking element in 130

brake-applying position, and means whereby said indicator serves to move said plate in a direction to cause said locking-arm to move said key-locking element from key-locking 5 position; substantially as described.

27. In a register, a clockwork mechanism, a brake therefor, an indicator coöoperating with said clockwork mechanism, a key-actuated part for driving said indicator, a lever having 10 an arm which lies in the path of withdrawal of an inserted key, connection between said lever and said brake, a pivoted plate movable toward and away from said lever, a locking-arm pivoted upon said plate and having movement into and out of engagement with said 15 lever to lock the latter in brake-applying position, and means whereby movement of said indicator serves to rock said plate whereby when said locking-arm is in locking engagement with said lever rocking of said plate serves to rock said lever to carry its key-locking arm into key-releasing position; substantially as described.

28. In a register, the combination with a 25 clock-train, an item-indicator driven thereby, and a totalizer, of a brake for said clock-train, driving connection between said item-indicator and said totalizer, said driving connection including a clutch, a removable tool for operating 30 said driving connection, and means whereby said clutch and said brake are operated through the instrumentality of said tool; substantially as described.

29. In a register, the combination with a 35 clockwork mechanism, an item-indicator, and a totalizer, of a brake for said clockwork mechanism, driving connection between said item-indicator and said totalizer and including a clutch, a tool-actuated part for driving 40 said driving connection, a tool for said part, a movable clutch-actuated member in the path of movement of the tool when being applied to said tool-actuated part, and a movable member connected to said brake and in said path 45 of movement of said tool, whereby upon application of said tool to said tool-actuated part said clutch and said brake are operated; substantially as described.

30. In a register, the combination with an 50 item-indicator, and a totalizer, of driving connection between said item-indicator and totalizer, said connection including a clutch, a key-operated driving part for said driving connection, a key for said part, and means 55 whereby upon the application of the key to said part said clutch is operated and said key is locked against withdrawal; substantially as described.

31. In a register, the combination with an 60 item-indicator, and a totalizer, of driving connection between said item-indicator and said totalizer, said connection including a clutch, a key-operated driving part for said driving connection, a key for said part means where- 65 by upon the application of the key to said

driving part said clutch is operated and said key is locked against withdrawal, and means whereby upon the resetting of said item-indicator said key is released; substantially as described.

70

32. In a register, the combination with a totalizer, an item-indicator having forward movement independent of said totalizer, and means for driving said item-indicator forwardly, of a key-actuated part, operative connection between said part and said item-indicator and totalizer whereby upon operation of said part said totalizer is advanced and said item-indicator is reset, means for locking an inserted key against withdrawal, and means, 80 operable in definite relationship to the operation of said indicator, for unlocking said key; substantially as described.

75

33. In a register, a movable indicator, a single driving mechanism for positively driving 85 said indicator to cause the latter to indicate any of a plurality of amounts, an arresting-dog for said indicator, means for determining the amount of movement to be permitted said indicator, and means for throwing said arresting-dog into arresting position when such predetermined amount of movement of said indicator has been reached and before said driving mechanism has reached the limit of its positive driving movement; substantially as 90 described.

90

34. In a register, an item-indicator, a totalizer, an arresting-dog for said totalizer movable into and out of arresting position, and means operable in definite relationship to the 100 operation of said item-indicator for operating said arresting-dog; substantially as described.

100

35. In a register, an item-indicator, a totalizer, an arresting-dog for said totalizer movable into and out of arresting position, an engaging member movable with said item-indicator, and a coöperating engaging member connected to said arresting-dog, whereby at a point in the movement of said item-indicator said engaging members are thrown into 110 engagement and said arresting-dog is operated; substantially as described.

105

36. In a register, a resettable item-indicator, a totalizer, means for advancing said item-indicator independently of said totalizer, means 115 for advancing said totalizer and for resetting said item-indicator, an arresting-dog, means whereby said arresting-dog arrests advance movement of said totalizer, and means whereby said arresting-dog also arrests resetting 120 movement of said item-indicator; substantially as described.

110

37. In a register, an indicator, an arresting-dog therefor, a movable plate having connection with said arresting-dog for operating the 125 latter, and means for operating said movable plate; substantially as described.

120

38. In a register, an item-indicator, a totalizer, an arresting-dog for said totalizer, a pivoted plate connected to said arresting-dog, an 130

130

engaging member movable with said item-indicator, and a coöperating engaging member carried by said pivoted plate; substantially as described.

5 39. In a register, a key-controlled indicator, an arresting-dog therefor, a key, a locking-dog for locking the inserted key against withdrawal, and operative connection between said arresting-dog and said locking-dog; substantially as described.

10 40. In a register, a key-controlled indicator, an arresting-dog therefor, a key, a locking-dog adapted to lock the inserted key against withdrawal, and means whereby when said arresting-dog is thrown into arresting position said locking-dog is thrown into releasing position; substantially as described.

15 41. In a register, a key-controlled indicator, an arresting-dog therefor, a key, a locking-dog adapted to lock the inserted key against withdrawal, a movable plate, connection between said plate and said arresting-dog, and connection between said plate and said locking-dog; substantially as described.

20 42. In a register, an item-indicator, a key-controlled totalizer, a key, a locking-dog for locking the inserted key against withdrawal, means for simultaneously arresting said item-indicator and said totalizer, and means whereby when said item-indicator and said totalizer are arrested said locking-dog is thrown into releasing position; substantially as described.

25 43. In a register, an item-indicator, a key-controlled totalizer, an arresting-dog therefor, a key, a locking-dog for locking the inserted key against withdrawal, means for arresting said item-indicator, and means whereby when said item-indicator is thus arrested said arresting-dog is thrown into arresting position and said locking-dog is thrown into releasing position; substantially as described.

30 44. In a register, an item-indicator, a key-controlled totalizer, a key, an arresting-dog for said totalizer, a locking-dog for preventing withdrawal of the inserted key, a movable plate, connection between said plate and said arresting-dog, connection between said plate and said locking-dog, an engaging member movable with said item-indicator, and a coöperating engaging member carried by said movable plate; substantially as described.

35 45. In a register, a movable indicator, an arresting-dog therefor and movable with said indicator, and means for returning said arresting-dog and the indicator through the amount of said movement; substantially as described.

40 46. In a register, a movable indicator, an arresting-dog therefor having movement with said indicator, and a recovering-spring coöperating with said arresting-dog and exerting itself against said movement of said arresting-dog; substantially as described.

45 47. In a register, a movable indicator, an arresting-dog therefor having movement with said indicator, and means for adjustably regu-

lating the amount of such movement of said arresting-dog; substantially as described.

48. In a register, a movable indicator, an arresting-dog therefor having movement with said indicator, and an adjustable stop-wedge for said arresting-dog; substantially as described.

53 49. In a register, a movable indicator, an arresting-dog therefor having movement with said indicator, a movable arm, and connection between said arm and said arresting-dog for throwing said arresting-dog into and out of arresting position and for permitting movement of said arresting-dog with said indicator independent of said arm; substantially as described.

58 50. In a register, a movable indicator, an arresting-dog therefor having movement with said indicator, and a movable arm for operating said arresting-dog, one of said last two mentioned elements being received in and having independent movement in a slot in the other thereof, whereby movement of said arm serves to throw said arresting-dog with relation to said indicator and said arresting-dog has movement with said indicator independent of said arm; substantially as described.

63 51. In a register, the combination with a clockwork mechanism, an item-indicator, and a key-operated totalizer, of a brake for said clockwork mechanism, driving connection between said clockwork mechanism and said item-indicator, driving connection between said item-indicator and said totalizer, a lever having one arm in the path of movement of an inserted key and forming a lock to prevent withdrawal of such inserted key, connection between the other arm of said lever and said brake, a lever-plate having an opening in one arm thereof, an arresting-dog for said totalizer and having movement with said totalizer, said arresting-dog being received in said opening in said lever-plate, a locking-arm pivotally connected to the other arm of said lever-plate and adapted to operatively engage and disengage said first-mentioned lever, a stop member movable with said item-indicator, and a coöperating stop member carried by said lever-plate; substantially as described.

68 52. In a register, the combination with a clock mechanism constituting a power-motor in driving connection with an item-indicator, a totalizer, a resettable indicator capable of making a plurality of revolutions, means for arresting said indicator at zero position and stopping said clock mechanism, said indicator in its resetting movement traveling a distance equal to that through which it traveled in its forward movement, and a totalizer which is operated proportionately to the resetting movement of the item-indicator.

73 53. In a register, a resettable indicator capable of making a plurality of revolutions, a stop member movable with said indicator, a coöperating stop member, means whereby

when said indicator makes one revolution in a forward direction one of said coöperating stop members is held out of stopping position with relation to the other of said stop members, and means whereby when said indicator has in its resetting movement been moved through a distance equal to the distance through which it advanced said coöperating stop members are in position to permit effective engagement of one of them by the other thereof; substantially as described.

54. In a register, a resettable indicator, a stop member movable therewith, a coöperating stop member, and a guiding member moving 15 able with said indicator and adapted to move said coöperating stop member toward and away from said stop member; substantially as described.

55. In a register, a resettable indicator, a stop member movable therewith, a guiding member movable with said indicator and having a groove leading toward and away from said stop member, and a coöperating stop member having a part received in said groove; 25 substantially as described.

56. In a register, a resettable indicator, a stop member movable therewith, a part movable with said indicator and having a spiral groove leading toward and away from said 30 stop member, and a coöperating stop member having a part received in said groove; substantially as described.

57. In a register, a casing provided with a keyhole, an arresting-plate within said casing and also provided with a keyhole, an indicator, a shutter therefor, a driving mechanism, a member controlling said driving mechanism, two movable elements one of which lies upon each side of said arresting- 40 plate, connection between one of said movable elements and said shutter, and connection between the other of said movable elements and said driving-mechanism-controlling member, in combination with two keys each of which 45 can be inserted through the keyhole in said casing, the respective said keys coöperating with the respective said movable elements, means whereby one of said keys is prevented from passing through said keyhole in said 50 arresting-plate, but said key is operable upon its said coöperating movable element when inserted through said keyhole in said casing, and means whereby the other of said keys can pass through both said keyholes and is operable upon its said coöperating movable element after it has passed through both said 55 keyholes; substantially as described.

58. In a register, a casing having a keyhole therein, an arresting-plate within said casing 60 and provided with a keyhole which is smaller than said first-mentioned keyhole, an indicator, a shutter therefor, a driving mechanism, a member for controlling said driving mechanism, two movable elements, one of which 65 is upon each side of said arresting-plate, con-

nexion between one of said movable elements and said shutter, and connection between the other of said movable elements and said driving-mechanism-controlling member, in combination with a key whose bit is of a size which 7c will permit it to pass through both said keyholes but is of a length greater than the distance between said arresting-plate and said casing, and a second key whose bit is of a size greater than said keyhole in said arresting- 75 plate and whose length is less than the distance between said casing and said arresting-plate; substantially as described.

59. In a register, an item-indicator adapted to indicate multiples of a unit and fractions 80 of said unit, a totalizer having provision for indicating multiples of said unit, means whereby the movement of said totalizer is controlled by the movement of said item-indicator, and means whereby the resultant movement of 85 said totalizer is such that said totalizer indicates a multiple of said unit notwithstanding the fact that the movement of the item-indicator which controlled such movement of said totalizer may have been such that the item- 90 indicator indicated an integral multiple of said unit and a fraction of said unit, such fraction of itself not remaining in said totalizer after the first actuation of said totalizer following the indication of said item-indica- 95 tor; substantially as described.

60. In a register, a totalizer having provision for indicating amounts in integral multiples of a unit, an item-indicator adapted to occupy positions representing multiples of 100 said unit and fractions of said unit, means whereby the movement of said totalizer is controlled by the position occupied by said item-indicator, and means whereby the resultant movement of said totalizer causes the 105 totalizer to indicate an integral multiple of said unit notwithstanding the fact that in its position controlling such movement of said totalizer the item-indicator may have indicated an integral multiple of said unit and a 110 fraction of said unit, said fraction of itself not remaining in said totalizer after the first actuation of said totalizer following the indication of said item-indicator; substantially as 115 described.

61. In a register, an item-indicator adapted to indicate multiples of a unit and fractions of said unit, a totalizer having provision for indicating multiples of said unit, means whereby the movement of said totalizer is controlled 120 by the movement of said item-indicator, and means whereby in the event that said item-indicator indicates a given multiple of said unit and a fraction of said unit less than a predetermined fraction of said unit the resultant 125 movement of said totalizer will cause said totalizer to indicate said definite multiple, the said fraction of said unit indicated by said item-indicator being disregarded in the said totalizer; substantially as described. 130

62. In a register, an item-indicator adapted to indicate multiples of a unit and fractions of said unit, a totalizer having provision for indicating multiples of said unit, and means whereby in the event that said item-indicator indicates a given multiple of a unit and a fraction of said unit greater than a predetermined fraction of said unit said totalizer will indicate said given multiple of said unit plus said unit; substantially as described.

63. In a register, an item-indicator adapted to indicate multiples of a unit and fractions of said unit, a totalizer having provision for indicating multiples of said unit, and means whereby in the event that said item-indicator indicates a given multiple of said unit and a fraction of said unit less than a predetermined fraction of said unit said totalizer will indicate said given multiple of said unit, while, in the event that said item-indicator indicates a given multiple of said unit and a fraction of said unit greater than said predetermined fraction, said totalizer will indicate said given multiple plus said unit; substantially as described.

64. In a register, an item-indicator, a totalizer whose extent of movement is controlled by said item-indicator, and means whereby said totalizer has an extent of resultant movement greater or less than the extent of movement of said item-indicator; substantially as described.

65. In a register, an item-indicator, a totalizer whose extent of movement is controlled by said item-indicator, means for permitting predetermined overthrow of said totalizer, and means for returning said totalizer through the extent of said predetermined overthrow; substantially as described.

66. In a register, an item-indicator, a totalizer, means for arresting movement of said item-indicator, a driving member movable with said totalizer, coöperating driving members movable with said item-indicator, said driving members being so arranged with relation to each other that when said totalizer is in a total-indicating position said driving member movable with said totalizer is spaced a distance from the position occupied by one of said other driving members when said item-indicator is in zero position, said distance being less than the distance between said driving members movable with said item-indicator, and means for returning said totalizer through said first-mentioned distance; substantially as described.

In testimony whereof I hereunto affix my signature, in the presence of two witnesses, this 15th day of December, 1903.

FRANCIS K. FASSETT.
